UNITED STATES PATENT OFFICE

ERNEST J. SCHUDA, OF ERIE, PENNSYLVANIA, ASSIGNOR TO LOVELL MANUFACTURING COMPANY, OF ERIE, PENNSYLVANIA, A CORPORATION OF PENNSYLVANIA

WRINGER

Application filed June 24, 1929. Serial No. 373,251.

Clothes wringers have heretofore been provided with safety devices by which the pressure of the rolls may be instantly released for any reason, such for instance, as when an operator's hand is caught between the rolls. Even with the complete release of pressure there is often quite serious injury even from the weight of the parts due to the continued turning of the roll. The present invention is designed to provide a means which is responsive immediately to the action of the safety release to break the driving connection to the rolls. Features and details of the invention will appear from the specification and claims.

A preferred embodiment of the invention is illustrated in the accompanying drawing as follows:—

Fig. 1 shows a front elevation of a portion of the wringer, partly in section.

Fig. 2 a section on the line 2—2 in Fig. 1.

Fig. 3 an end view of the driving clutch and actuating mechanism.

Fig. 4 a section on the line 4—4 in Fig. 1.

Figs. 5 and 6 show detailed views of parts 25 and 39.

1 marks the base of the frame, 2 the side stiles of box form, and 3 the wringer top, the wringer top being detachable. 4 marks the lower roll, 5 the upper roll, and 6 and 7 roll shafts. The lower roll shaft is journaled in a block 8 resting on a step 9 within the stile. 10 is a bearing block for the upper roll slid- 35 ily mounted in the stile. A pressure spring 11 rests on the blocks 10.

The release device has a sleeve 12 through which an adjusting screw 13 extends and is connected to the spring by a fitting 14. The sleeve extends through an opening 16 in the fitting 15. This opening has extensions 16a. A shoulder 17 is arranged on the sleeve and operates on a cam 18 on the under-side of the fitting 15. The sleeve 12 is provided with a handle 19. When the sleeve is turned in either direction the shoulders 17 are brought

into register with the extensions 16a and this permits the sleeve to slide through the fitting, thus releasing pressure on the spring. This scheme of release device is illustrated in the Misner Reissue Patent #15,865, June 24th, 1924.

The top bar 3 is detachable. A latch 20 is mounted on a cross pin 21. The latch has a hook 22 which engages a shoulder 23 on the stile 2. The latch 20 has two sides with a connecting bar 20a. This connecting bar is in the path of the spring 11 when it is thrown up upon release. As the spring contacts the latch it detaches the hook from the shoulder 23 and releases the detachable top 60 3 so as to give unlimited freedom to the lifting of the top roll.

The hook is positioned initially by an extension 24 on the latch which contacts the top wall so that as the top bar is put in place 65 the hook will be in position to move into engagement with the shoulder 23.

A bail 25 extends around a shaft 27 and has slots 26 at its upper end through which the bolt 21 extends so that as the top bar is lifted 70 the top roll is also lifted from the frame.

The drive shaft 6 has a radially extending pin 28 which operates in a clutch slot 29 in a clutch head 30. The head has an extending sleeve 31 which extends over a drive shaft 75 33. The sleeve is locked to rotate with the shaft 33 by a spline 32 but is free to slide thereon axially. The sleeve has a slot 34 and arms 35 of a lever 36 extend into this slot and by engagement with the walls of the 80 slot throw the clutch into and out of engagement, the clutch notch, or detent 29 being drawn away, or thrown into engagement with the pin 28. The lever 36 is pivoted at 37 on the frame and the inner end of the 85 lever engages a bar 38 on an actuator 39. The actuator extends up along the lower bearing block 8, the bearing block having grooves 40 for guiding the actuator. The actuator has a forwardly extending plate 41 90

and springs 42 are tensioned between this plate and the bearing block 8. Projections 43 are arranged on the projection 41 and projections 44 on the bearing block, thus retaining the springs in place.

- 5 When the top bar is in place and the latch hook 22 under the shoulder 23 the bail is in its lowest position and engages the top of the actuator and forces the actuator down to the position shown in Fig. 1 and in this 10 position the actuator acting through the lever 36 sets the clutch and maintains the driving connection for the wringer. But when the latch is released and the top bar is lifted the bail 25 is also released and when this happens 15 the springs 42 operate the actuator and through the lever 36 detach, or release the clutch. Thus automatically the operator is not only relieved of the pressure but also of the continued rotation of the rolls.

20 What I claim as new is:—

1. In a wringer, the combination of a frame; wringer rolls in the frame; means exerting pressure on the rolls; a driving connection for the rolls; a safety release device 25 adapted to quickly release the pressure on the rolls; and means automatically breaking the driving connection subsequent to the release of pressure on the rolls comprising an actuator depressed through pressure on the 30 rolls, a spring lifting the actuator on the release of pressure, and means conveying the movement of the actuator to the driving connection.

35 2. In a wringer, the combination of a frame comprising a side stile and a detachable top bar; wringer rolls in the frame having roll shafts; bearing blocks in the stile for the rolls; means exerting pressure on the rolls; a driving connection for the rolls comprising a clutch; a bail extending around the upper roll shaft carried by the top bar; a safety release device adapted to quickly release the pressure on the rolls and the top 40 bar; and means responsive to a movement 45 of the bail releasing the clutch.

3. In a wringer, the combination of a frame; wringer rolls in the frame; means exerting pressure on the rolls; a driving connection for the rolls; a safety release device adapted to quickly release pressure on the rolls; means connected with the release device having an upward movement upon the operation of the safety release; a bearing for the bottom roll; an actuator extending around the bearing and engaged by the means; a spring operating on the actuator and tending to lift the same; a driving connection for the wringer; and means actuated by the actuator breaking the driving connection when the actuator is released by the safety device.

4. In a wringer, the combination of a frame; wringer rolls in the frame; means exerting pressure on the rolls; driving means

for the rolls; a safety release device adapted to quickly release the pressure on the rolls; and means controlling the driving means acting upon the release of pressure on the rolls and stopping the action of the driving means 70 subsequent to the release of pressure on the rolls.

In testimony whereof I have hereunto set my hand.
